UNITED STATES PATENT OFFICE.

ORTUS E. MOATS, OF CHICAGO, ILLINOIS, ASSIGNOR TO WESTERN WHEELED SCRAPER COMPANY, OF AURORA, ILLINOIS, A CORPORATION OF ILLINOIS.

EXCAVATING AND GRADING MACHINE.

Application filed November 5, 1920. Serial No. 421,828.

To all whom it may concern:

Be it known that I, ORTUS E. MOATS, a citizen of the United States, and a resident of Chicago, in the county of Cook and State of Illinois, have invented certain new and useful Improvements in Excavating and Grading Machines, of which the following is a specification, reference being had to the accompanying drawings.

10 My invention relates to road making machinery and has for its object to provide an improved machine suitable for use in scraping and conveying earth in making and grading roads. The nature of my improvements will fully appear from the illustrated embodiment thereof in connection with the detailed description of the illustrated construction. What I regard as new is set forth in the claims.

20 In the accompanying drawings:

Fig. 1 is a plan view of my improved machine;

Fig. 2 is a side elevation thereof;

Fig. 3 is a partial perspective view of the 25 earth scraping and conveying member; and

Fig. 4 is a detail, being a horizontal section on line 4—4 of Fig. 2.

Referring to the drawings, it will be seen that my improved machine comprises a 30 main frame 5 having front steering wheels 6 and rear wheels 7. The latter wheels are preferably mounted on extensible axle members 8, 9, the position of which is controlled by hand wheels 10, 11 in the well-known way. At the rear of the frame is an operator's platform 12, as usual. 13 indicates the driver's seat, and 14 indicates the tongue, which is provided with a rearward extension 15 as shown in Figs. 1 and 2. 16 indicates the front axle which in the construction shown is pivoted to turn with the tongue, in the usual way, but I wish it to be understood that so far as my invention is concerned the machine may be arranged to be 45 steered in any of the well-known ways employed in the art.

Arranged beneath the frame 5 and between the front and rear wheels is an earth grading and conveying member which comprises a scraper 17 from the upper marginal portion of which rises a back plate 18. The scraper 17 is disposed transversely with reference to the frame 5, and the back plate 18 thereof also extends transversely thereof.

At the end portions of the back plate 18 are wings 19 which extend forward therefrom, the upper and lower margins of said wings being preferably level with the corresponding margins of said back plate. The lower margins of said wings therefore are 60 some little distance above the cutting edge of the scraper 17. 20 indicates a cross-brace which connects and braces the forward margins of the wings 19, as shown in Figs. 1 and 3. Preferably the front margins of said wings are reenforced by angle iron strips 21, as shown in Fig. 3. 22 indicates a pair of forwardly-extending draft bars which are secured to the intermediate portion of the back plate 18 at a distance from each other and are braced thereto by plates 23 and angle irons 24, as shown in Fig. 3. They are also connected by a cross-brace 25. At their forward ends the draft bars 22 converge and are curved to form a gooseneck 26 which is 70 connected with the rearward extension 15 of the tongue, as shown in Fig. 2. Thus the draft is transmitted directly to the back plate 18 and through it to the scraper 17.

The earth scraping and conveying member is suspended from the frame 7 by rack-bars 27, the lower end portions of which are pivotally connected with the draft bars 22 by means of pivots 28 which extend through the end portions of the brace 25, as shown in Figs. 2 and 3. The upper end portions of said rack-bars pass between pinions 29 and anti-friction rollers 30, as illustrated in Fig. 4, the rack portion of said bars being in mesh with said pinions so that when the pinions are rotated the rack bars are moved vertically. The rollers 30 serve to hold the rack bars in mesh with said pinions without interfering with their endwise or lateral movement.

Preferably two of the anti-friction rollers are provided in connection with each rack bar, and they are mounted so as to be capable of swinging about the axes of the pinions 29, as shown and described in Patent No. 584,395 to Thomas R. McKnight, dated June 15, 1897, and as illustrated in Figs. 2 and 4. The pinions 29 are mounted upon short shafts 31 journaled in brackets 32 which are carried by supporting blocks 33 mounted on standards 34 which rise from the side members of the frame 5. The blocks 33 are connected to the standards 34

by bolts 35 which pass through said standards and through arcuate slots in the blocks 33 so that slight axial adjustment of said blocks is permitted. 36 indicates bolts which 5 connect the brackets 32 with the blocks 33 so that said brackets are capable of swinging about the bolts 36 as may be necessary in the operation of the machine.

The shafts 31 are provided with universal 10 couplings 37 which connect them with horizontally-disposed operating rods 38 arranged to be actuated by hand wheels 39 through bevelled pinions 40, 41, as shown in Figs. 1 and 2, said universal couplings 15 being provided to accommodate the rocking or swinging of the brackets 32 above referred to. The hand wheels 39 are mounted on transverse shafts 42 mounted in brackets 43 supported by standards 44 which rise 20 from the frame 5, as shown in Figs. 1 and 2. 45 indicates brake drums cooperating with strap brakes of the usual type for locking the rack bars in their different positions of adjustment. This mechanism for 25 raising and lowering the rack bars 27 is substantially the same as that which has long been in use on road grading machines, and, so far as its specific construction is concerned, forms no part of my invention, 30 as any suitable mechanism for the purpose may be employed for raising or lowering the earth scraping and conveying member.

In the use of my improved machine the 35 scraper 17 loosens the earth and levels the inequalities of the roadway, the loosened earth being piled up in advance of the back plate 18 and between the wings 19, so that as the machine advances the loosened earth is conveyed along the roadway and is either deposited in hollows where they occur, or may 40 be conveyed to any place where it is desired to dump it. By means of the rack bars the scraper is held down to its work and may be adjusted vertically to vary the grade at 45 which the scraper operates. As the draft is applied directly to the upper portion of the back plate 18 the earth scraping and conveying member is held from tipping backward and the load is moved to the best 50 advantage. This construction also makes it practicable to make the back plate 18 and the wings 19 of comparatively light material so that the weight of this part of the machine is not objectionable. The construction 55 of the earth scraping and grading member is also such that it is well adapted for attachment to carriages of various types, and also it may very readily be removed so that an ordinary scraper may be substituted 60 for it where the work to be performed makes such substitution desirable.

To steady and support the earth scraping and grading member without interfering with its vertical adjustment, a swinging 65 brace 46 is provided which, as best shown

in Fig. 1, has somewhat the shape of a crank, one end being loosely journaled in the upper portion of the back plate 18, preferably about the center thereof, while the other end of said brace is journaled in a transverse 70 bar 47 secured to the frame 5, as shown in Fig. 2. By this construction when the scraping and grading member is vertically adjusted the brace 46 swings in a transverse 75 vertical plane to adapt itself to the changed position of said member and does not interfere with such vertical adjustment.

What I claim as my invention and desire to secure by Letters Patent, is—

1. In an excavating and grading machine, 80 the combination with a frame having front and rear wheels and a draft device, of an earth scraping and conveying member comprising a scraper disposed transversely beneath said frame between said front and rear wheels, a transverse back plate rising from said scraper, side wings extending forward from the end portions of said back plate, forwardly extending draft bars rigidly secured to the front face of said back plate 90 and extending forward therefrom for connecting said member with the draft device, and means mounted on said frame and connected with said member for holding it down in operative position. 95

2. In an excavating and grading machine, the combination with a frame having front and rear wheels and a draft device, of an earth scraping and conveying member comprising a scraper disposed transversely beneath said frame between said front and rear wheels, a transverse back plate rising from 100 said scraper, side wings extending forward from the end portions of said transverse back plate, means connecting said member with the draft device, vertically and laterally movable bars mounted on said frame and connected with said member for holding it down in operative position, and a swinging 105 brace connecting the upper portion of said transverse back plate with said frame. 110

3. In an excavating and grading machine, the combination with a frame having front and rear wheels and a draft device, of an earth scraping and conveying member comprising a scraper disposed transversely beneath said frame between said front and rear wheels, a transverse back plate rising from 115 said scraper, side wings extending forward from the end portions of said transverse back plate, means connecting said member with the draft device, vertically and laterally movable bars mounted on said frame and connected with said member in advance of said back plate for adjusting 120 said member vertically, and a swinging brace connecting the upper portion of said transverse back plate with said frame. 125

4. In an excavating and grading machine, the combination with a frame having front 130

and rear wheels and a draft device, of an earth scraping and conveying member comprising a scraper disposed transversely beneath said frame between said front and rear wheels, a transverse wall rising from said scraper, side wings extending forward from the end portions of said transverse

wall, means connecting said member with the draft device, means mounted on said frame and connected with said member for adjusting it vertically, and a swinging brace connecting the upper portion of said transverse wall with said frame. ¹⁰
